VERTICAL BORING MILL ATTACHMENT

Manuel Turchan, Dearborn, Mich.

Application June 25, 1949, Serial No. 101,323

7 Claims. (Cl. 77—4)

1

This invention relates to vertical boring mills, and more particularly to a hydraulic duplicating attachment operable in conjunction with such boring mills.

It is the object of this invention to provide in such vertical boring mill a hydraulic duplicating attachment with the movements of an angularly inclined slide being effected by a hydraulic cylinder controlled by a hydraulic tracer responding to the surface of a template.

It is the further object of this invention to provide in such mill a vertically adjustable slide, a horizontally adjustable slide thereon, and a third upwardly inclined angularly arranged slide reciprocally arranged upon said horizontally adjustable slide, said third slide being arranged at an acute angle to the vertical axis of the rotatable worktable which forms a part of said mill.

It is the further object of this invention to provide in conjunction with said vertical boring mill a horizontally reciprocal slide upon which is mounted an upwardly inclined reciprocal slide arranged at an angle less than 90 degrees to the direction of movement of said horizontally movable slide.

These and other objects will be seen from the following specification and claims in conjunction with the appended drawings in which:

Figure 1 is a front elevational view of the angular attachment for a vertical boring mill fragmentarily shown.

Figure 2 is a right side elevational view thereof.

Figure 3 is a fragmentary front elevational view similar to Figure 1 but with the workpiece inverted; and

Figure 4 is a fragmentary diagrammatic view showing the hydraulic cylinder, the tracer head and the hydraulic fluid pressure supply unit, together with the hydraulic connections therebetween.

It will be understood that the above drawings illustrate merely a preferred embodiment of the invention and that other embodiments are contemplated within the scope of the claims hereinafter set out.

Referring to the drawings a vertical boring mill is fragmentarily shown including the rotatable table 11 with workpiece supporting chuck 12 upon which is mounted workpiece 13, the interior surface 14 of which is being machined.

Upright slide support 15 with vertically arranged guideways 16 forms a part of and is attached to the bed of said vertical boring mill, and has adjustably mounted thereon the verti-

2

cally adjustable slide 17. The latter has formed therein horizontally arranged guideways 18, upon and relatively to which is mounted horizontally adjustable slide 19.

It will be noted that vertically adjustable slide 17 may be controlled in any conventional manner such as by a hand operated lead screw, and similarly the horizontally adjustable slide 19 may be controlled in any conventional manner such as by a hand or power operated lead screw to thereby effect horizontal movements of slide 19 relative to its support 17.

Slide 17 as well as slide 19 thereon are arranged in upright position, and angularly inclined slide support 20 is secured to and forms a part of horizontally adjustable slide 19. The longitudinal axis of slide support 20 extends upwardly and is inclined at an angle to the direction of movement of horizontally adjustable slide 19.

Similarly inclined reciprocal slide 21 is mounted upon slide support 20 and retained thereon by suitable guideways, slide 21 having secured thereto at its upper end transverse plate 22 to which is secured hydraulic cylinder 23. Stationary piston rod 24 with its associated piston 25 is arranged within reciprocal cylinder 23, with the lower end of rod 24 being secured to angular slide support 20 at point 26.

Inlet pipe 27 is adapted to supply pressure fluid to the lower end of cylinder 23, and inlet pipe 28 is adapted to alternately supply pressure fluid to the opposite end of said cylinder, in a manner hereinafter set out in detail. It is contemplated however, that if pressure fluid is supplied to the interior of cylinder 23 through the pipe 27, that in that case exhaust fluid from the opposite end of said cylinder will escape through the other pipe 28.

Tool head 29 is mounted upon the lower end of angular slide 21 and carries toolholder 30 from which depends cutting tool 31, which as shown in Figure 1 is adapted to operatively engage the interior surface 14 of workpiece 13 mounted upon rotatable table 11 which forms a part of a conventional vertical boring mill.

Hollow triangularly shaped bracket 32 is joined to angularly inclined slide 21 at points 33 and 34 and has at its lower end a hollow collar 35 which is adapted to supportably receive and retain the cylindrical barrel 36 of the hydraulic tracer employed.

A tracer head 37 is arranged at one end of said barrel and includes a movable valve element 37' engaged at one end by a coil spring 37'' supported within said tracer head. Tracer arm 38

is centrally arranged within barrel 36 and at its inner end cooperatively engages the tracer valve 37', while its opposite end projects outwardly from barrel 36 and has at its outer end the tracer tip or contactor 39 which is adapted to cooperatively engage the edge of template 40.

It will be understood that the tracer mechanism above described very briefly is a hydraulic universal type tracer which is spring biased for effecting movement in one direction of the tracer spindle 38, with movement in the opposite direction of said spindle being effected by the thrust of the template with respect to the tracer tip.

In any event the detail of construction of the tracer mechanism forms no part of the present invention and for this reason its detail of construction is omitted. It is sufficient to state that the valve element 37' within tracer head 37 by its movements controls the delivery of pressure fluid out of either of the cylinder ports 45 or 46 and through the cylinder operating pipes 27 or 28 respectively. It will be understood that with the tracer tip 39 merely engaging the surface of template 40, and with there being no feed movement of the horizontally movable slide 19 that the tracer valve will be in a neutral position and there will be no flow of fluid through either of the pipes 27 or 28.

Referring to Figure 4 there is diagrammatically shown at 47 a hydraulic fluid supply unit which includes a sump and a pump in conjunction therewith which is adapted to supply pressure fluid at a pre-determined pressure at port 48 and through the connecting supply pipe 49 which is joined at its other end to the tracer head at inlet port 50.

This pressure fluid supplied to the tracer head 37 is adapted to be delivered out through either of the cylinder pipes 27 or 28 depending upon the positioning of the tracer valve 37' under the control of the spring 37" and the tracer spindle 38 responding to the surface of the template 40. Now in the neutral position of said valve above referred to the pressure fluid supplied to the tracer head at port 50 will be blocked off by said valve and will not flow through either of the pipes 27 or 28.

If the tracer valve is moved in one direction from the neutral position then pressure fluid will be supplied through pipe 27 for example, and exhaust fluid from the opposite end of cylinder 23 will be returned to the tracer head through the pipe 28, and this fluid will be exhausted through the tracer valve and out from tracer head 37 through the exhaust port 53 which is connected to exhaust opening 51 in the hydraulic unit 47 by the conduit 52.

Now assuming that the tracer valve is moved in the opposite direction from the neutral position above described, then in that case pressure fluid coming into tracer head 37 at port 50 is delivered through cylinder pipe 28 to the opposite end of cylinder 23, and the exhaust fluid upon the opposite side of the piston within said cylinder is returned to the tracer head through the pipe 27 and into port 45, through the tracer valve and is thence exhausted through port 53 and exhaust pipe 52 back to the hydraulic unit.

With pressure fluid delivered through the pipe 27 it is apparent that the cylinder 23 will move inwardly effecting a corresponding inward movement of the angularly inclined cutter supporting slide 21; and likewise with pressure fluid delivered to the pipe 28 cylinder 23 will move outwardly.

Template 40 is mounted and secured upon

template holder 41' and is adapted for horizontal adjustment thereon upon the guideway 41". Holder 41' is secured upon the upper end of the formed supporting arm 41, and the lower end of said arm is secured to the horizontally adjustable slide 43 by the screws 42. The slide 43 as shown in Figures 1 and 2 is retained within the guide arm 44 which projects outwardly from the mill bed and which is adapted to permit horizontal adjustments of slide 43 which carries the template 40.

Referring to Figure 4 there is shown an additional port 56 at the lower end of the tracer head 37 which is a vacuum port and which is joined to a corresponding port 54 of hydraulic unit 47 by a conduit 55. Arranged within said hydraulic unit is a device which forms no part of the present invention but which is adapted to create a vacuum or reduced pressure condition in communication with port 54 and the conduit 55. By this construction any fluid seepage within the tracer head 37 may be withdrawn from the interior thereof and returned to the hydraulic unit 47.

Operation

In the operation of this attachment for a vertical boring mill as shown in Figure 1 the workpiece 13 is rotated by the table 11 on a vertical axis, while the cutter 31 is removing metal from the interior surface 14 of said workpiece in a conventional mill operation. However, in addition the upright horizontally adjustable slide 19 is adapted to be fed in one direction or the other by suitable lead screw so that the entire interior surface of the workpiece may be traversed, with the lateral edge of the tracer tip or contactor 39 responding to the surface of the template 40 to thereby control the position of the cutter 31 during feed movement of the slide 19. When the edge of tracer tip 39 is out of contact with the top edge of template 40, spring 37" within tracer head 37, Fig. 2, moves valve 37' into extreme negative position, i. e. to the right. Pressure fluid through tracer inlet port 50, Fig. 4, is then directed by valve 37' out cylinder pipe 27 causing inward movement of cylinder 23 until the edge of tracer tip 39 carried by slide 21 is in engagement with the top edge of template 40.

This lateral pressure engagement between said template and the edge of tracer tip 39 causes the tracer spindle 38 and valve 37' to move inwardly to the left against the action of spring 37", to a central neutral position. In this position there will be no flow of pressure fluid through tracer head 37 to either end of cylinder 23.

Now when the lateral edge of tracer tip 39 engages a rise in the edge of the template 40, there is an increased impedance or lateral pressure developed between said template and tracer tip causing a movement of the tracer spindle and the valve 37' to move to the left of said neutral position. In this position of valve 37' pressure fluid is directed through pipe 28 causing cylinder 23 to move outwardly until said increased lateral pressure is reduced to the point that valve 27' is back in neutral position and the flow of fluid and movement of said cylinder stops. The universal tracer mechanism above described is more fully disclosed in the following patents of the applicant: 2,386,825; 2,390,566; 2,301,719; 2,374,714; 2,331,817; 2,389,653; and 2,402,306.

Now as shown in Figure 3, the arrangement is the same however the cutter 31 is now working over the exterior surface 14' of workpiece 13,

and for this operation a different template 40' is employed. Consequently by the present construction employing an upright horizontally adjustable slide, and in conjunction therewith an upwardly inclined angular slide, it is possible for a single tracer and a single hydraulic cylinder to control the reciprocal movements of the upwardly inclined angular slide which carries the cutting tool whereby with the workpiece mounted upon said rotatable table of the vertical boring mill, it is possible to completely form the interior and exterior surfaces of the workpiece.

Having described my invention reference should now be had to the claims which follow for determining the scope thereof.

I claim:

1. A vertical boring mill for reproducing tapers, curves, and right angle shoulders on the work in conformity with the profile of a template, including a horizontal rotatable table for holding and turning a work; an upright slide support with vertically arranged guideways, an upright vertically adjustable slide thereon, an upright horizontally adjustable slide movably mounted upon said vertically adjustable slide, means on said first slide for guiding said second slide longitudinally of the work, means for moving said horizontally movable slide at a constant rate of advance, a template disposed in fixed position lying in a plane parallel to the path of movement of said horizontally movable slide, with its profile in a plane parallel to said path of movement, an upwardly inclined slide support mounted on said horizontally movable slide and arranged at an acute angle to the direction of movement of said latter slide, and with said inclined slide support having similarly inclined guideways thereon, a correspondingly inclined slide mounted on said latter guideways and adapted to reciprocate at an angle to the work acute in the direction of travel of said horizontally movable slide, a work engaging cutter on said inclined slide, an upright bracket secured to said inclined slide and projecting laterally thereof, a tracer mechanism mounted on said bracket with its longitudinal axis at right angles to the plane of said template and having a finger projecting longitudinally of said tracer mechanism engaging the profile of said template and responsive to lateral thrust relatively to said tracer mechanism in the plane of said profile and responsive to relief and impedance from said template, and a hydraulic system including a cylinder and piston for reciprocating the inclined slide, said cylinder being secured to said inclined slide and said piston being joined to said inclined slide support, said system so connecting the tracer and the cylinder that actuation of the tracer finger by the template operates the cylinder to move the inclined slide to neutralize the actuation of said tracer finger, thus reproducing on the work the profile of said template, said finger being universally movable, said template being mounted in a plane offset from the planes of said slides.

2. A vertical boring mill for reproducing tapers, curves, and right angle shoulders on the work in conformity with the profile of a template, including a horizontal rotatable table for holding and turning a work; an upright slide support with vertically arranged guideways, an upright vertically adjustable slide thereon, an upright horizontally adjustable slide movably mounted upon said vertically adjustable slide, means on said first slide for guiding said second slide longitudinally of the work, means for moving said horizontally movable slide at a constant rate of advance, a template disposed in fixed position lying

in a plane parallel to the path of movement of said horizontally movable slide, with its profile in a plane parallel to said path of movement, an upwardly inclined slide support mounted on said horizontally movable slide and arranged at an acute angle to the direction of movement of said latter slide, and with said inclined slide support having similarly inclined guideways thereon, a correspondingly inclined slide mounted on said latter guideways and adapted to reciprocate at an angle to the work acute in the direction of travel of said horizontally movable slide, a work engaging cutter on said inclined slide, an upright bracket secured to said inclined slide and projecting laterally thereof, a tracer mechanism mounted on said bracket with its longitudinal axis at right angles to the plane of said template and having a finger projecting longitudinally of said tracer mechanism engaging the profile of said template and responsive to lateral thrust relatively to said tracer mechanism in the plane of said profile and responsive to relief and impedance from said template, and a hydraulic system including a cylinder and piston for reciprocating the inclined slide, said cylinder being secured to said inclined slide and said piston being joined to said inclined slide support, said system so connecting the tracer and the cylinder that actuation of the tracer finger by the template operates the cylinder to move the inclined slide to neutralize the actuation of said tracer finger, thus reproducing on the work the profile of said template, said finger being universally movable, said template being mounted in a plane offset from the planes of said slides.

3. A vertical boring mill for reproducing tapers, curves, and right angle shoulders on the work in conformity with the profile of a template, including a horizontal rotatable table for holding and turning a work; an upright slide support with vertically arranged guideways, an upright vertically adjustable slide thereon, an upright horizontally adjustable slide movably mounted upon said vertically adjustable slide, means on said first slide for guiding said second slide longitudinally of the work, means for moving said horizontally movable slide at a constant rate of advance, a template disposed in fixed position lying in a plane parallel to the path of movement of said horizontally movable slide, with its profile in a plane parallel to said path of movement, an upwardly inclined slide support mounted on said horizontally movable slide and arranged at an acute angle to the direction of movement of said latter slide, and with said inclined slide support having similarly inclined guideways thereon, a correspondingly inclined slide mounted on said latter guideways and adapted to reciprocate at an angle to the work acute in the direction of travel of said horizontally movable slide, a work engaging cutter on said inclined slide, an upright bracket secured to said inclined slide and projecting laterally thereof, a tracer mechanism mounted on said bracket with its longitudinal axis at right angles to the plane of said template and having a finger projecting longitudinally of said tracer mechanism engaging the profile of said template and responsive to lateral thrust relatively to said tracer mechanism in the plane of said profile and responsive to relief and impedance from said template, and a hydraulic system including a cylinder and piston for reciprocating the inclined slide, said cylinder being secured to said inclined slide and said piston being joined to said inclined slide support,

said system so connecting the tracer and cylinder that actuation of the tracer finger by the template operates the cylinder to move the inclined slide to neutralize the actuation of said tracer finger, thus reproducing on the work the profile of said template, said finger being universally movable, said cylinder being mounted on said inclined slide and extending outwardly from the upper end thereof.

4. A vertical boring mill for reproducing tapers, curves, and right angle shoulders on the work in conformity with the profile of a template, including a horizontal rotatable table for holding and turning a work; an upright slide support with vertically arranged guideways, an upright vertically adjustable slide thereon, an upright horizontally adjustable slide movably mounted upon said vertically adjustable slide, means on said first slide for guiding said second slide longitudinally of the work, means for moving said horizontally movable slide at a constant rate of advance, a template disposed in fixed position lying in a plane parallel to the path of movement of said horizontally movable slide, with its profile in a plane parallel to said path of movement, an upwardly inclined slide support mounted on said horizontally movable slide and arranged at an acute angle to the direction of movement of said latter slide, and with said inclined slide support having similarly inclined guideways thereon, a correspondingly inclined slide mounted on said latter guideways and adapted to reciprocate at an angle to the work acute in the direction of travel of said horizontally movable slide, a work engaging cutter on said inclined slide, an upright bracket secured to said inclined slide and projecting laterally thereof, a tracer mechanism mounted on said bracket with its longitudinal axis at right angles to the plane of said template and having a finger projecting longitudinally of said tracer mechanism engaging the profile of said template and responsive to lateral thrust relatively to said tracer mechanism in the plane of said profile and responsive to relief and impedance from said template, a hydraulic system including a cylinder and piston for reciprocating the inclined slide, said cylinder being secured to said inclined slide and said piston being joined to said inclined slide support, said system so connecting the tracer and the cylinder that actuation of the tracer finger by the template operates the cylinder to move the inclined slide to neutralize the actuation of said tracer finger, thus reproducing on the work the profile of said template, said finger being universally movable, and an upright stationary template holder lying in a plane parallel to the planes of said slides and having a horizontal guideway, said template being mounted in said guideway and adapted for horizontal adjustments therein.

5. A vertical boring mill for reproducing tapers, curves, and right angle shoulders on the work in conformity with the profile of a template, including a horizontal rotatable table for holding and turning a work; an upright slide support with vertically arranged guideways, an upright vertically adjustable slide thereon, an upright horizontally adjustable slide movably mounted upon said vertically adjustable slide, means on said first slide for guiding said second slide longitudinally of the work, means for moving said horizontally movable slide at a constant rate of advance, a template disposed in fixed position lying in a plane parallel to the path of movement of said horizontally movable slide, with its profile in a plane parallel to said path of movement, an upwardly inclined slide support mounted on said horizontally movable slide and arranged at an acute angle to the direction of movement of said latter slide, and with said inclined slide support having similarly inclined guideways thereon, a correspondingly inclined slide mounted on said latter guideways and adapted to reciprocate at an angle to the work acute in the direction of travel of said horizontally movable slide, a work engaging cutter on said inclined slide, an upright bracket secured to said inclined slide and projecting laterally thereof, a tracer mechanism mounted on said bracket with its longitudinal axis at right angles to the plane of said template and having a finger projecting longitudinally of said tracer mechanism engaging the profile of said template and responsive to lateral thrust relatively to said tracer mechanism in the plane of said profile and responsive to relief and impedance from said template, a hydraulic system including a cylinder and piston for reciprocating the inclined slide, said cylinder being secured to said inclined slide and said piston being joined to said inclined slide support, said system so connecting the tracer and the cylinder that actua-

horizontally movable slide and arranged at an acute angle to the direction of movement of said latter slide, and with said inclined slide support having similarly inclined guideways thereon, a correspondingly inclined slide mounted on said latter guideways and adapted to reciprocate at an angle to the work acute in the direction of travel of said horizontally movable slide, a work engaging cutter on said inclined slide, an upright bracket secured to said inclined slide and projecting laterally thereof, a tracer mechanism mounted on said bracket with its longitudinal axis at right angles to the plane of said template and having a finger projecting longitudinally of said tracer mechanism engaging the profile of said template and responsive to lateral thrust relatively to said tracer mechanism in the plane of said profile and responsive to relief and impedance from said template, a hydraulic system including a cylinder and piston for reciprocating the inclined slide, said cylinder being secured to said inclined slide and said piston being joined to said inclined slide support, said system so connecting the tracer and the cylinder that actuation of the tracer finger by the template operates the cylinder to move the inclined slide to neutralize the actuation of said tracer finger, thus reproducing on the work the profile of said template, said finger being universally movable, and an upright stationary template holder lying in a plane parallel to the planes of said slides and having a horizontal guideway, said template being mounted in said guideway and adapted for horizontal adjustments therein.

6. A vertical boring mill for reproducing tapers, curves, and right angle shoulders on the work in conformity with the profile of a template, including a horizontal rotatable table for holding and turning a work; an upright slide support with vertically arranged guideways, an upright vertically adjustable slide thereon, an upright horizontally adjustable slide movably mounted upon said vertically adjustable slide, means on said first slide for guiding said second slide longitudinally of the work, means for moving said horizontally movable slide at a constant rate of advance, a template disposed in fixed position lying in a plane parallel to the path of movement of said horizontally movable slide, with its profile in a plane parallel to said path of movement, an upwardly inclined slide support mounted on said horizontally movable slide and arranged at an acute angle to the direction of movement of said latter slide, and with said inclined slide support having similarly inclined guideways thereon, a correspondingly inclined slide mounted on said latter guideways and adapted to reciprocate at an angle to the work acute in the direction of travel of said horizontally movable slide, a work engaging cutter on said inclined slide, an upright bracket secured to said inclined slide and projecting laterally thereof, a tracer mechanism mounted on said bracket with its longitudinal axis at right angles to the plane of said template and having a finger projecting longitudinally of said tracer mechanism engaging the profile of said template and responsive to lateral thrust relatively to said tracer mechanism in the plane of said profile and responsive to relief and impedance from said template, a hydraulic system including a cylinder and piston for reciprocating the inclined slide, said cylinder being secured to said inclined slide and said piston being joined to said inclined slide support, said system so connecting the tracer and the cylinder that actua-

tion of the tracer finger by the template operates the cylinder to move the inclined slide to neutralize the actuation of said tracer finger, thus reproducing on the work the profile of said template, said finger being universally movable, said boring mill including a bed, a horizontal guide arm joined to said bed, and extending outwardly therefrom parallel to the plane of said first slide, a slide mounted on said guide arm adapted for horizontal adjustments, an upright support arm on said latter slide, and an upright template holder on the upper end of said arm and having a horizontally extending guideway therein, said template being adjustably mounted in said guideway.

7. A vertical boring mill for reproducing tapers, curves, and right angle shoulders on the work in conformity with the profile of a template, including a horizontal rotatable table for holding and turning a work; an upright slide support with vertically arranged guideways, an upright vertically adjustable slide thereon; an upright horizontally adjustable slide movably mounted upon said vertically adjustable slide, means on said first slide for guiding said second slide longitudinally of the work, means for moving said horizontally movable slide at a constant rate of advance, a template disposed in fixed position lying in a plane parallel to the path of movement of said horizontally movable slide, with its profile in a plane parallel to said path of movement, an upwardly inclined slide support mounted on said horizontally movable slide and arranged at an acute angle to the direction of movement of said latter slide, and with said inclined slide support having similarly inclined guideways thereon, a correspondingly inclined slide mounted on said latter guideways and adapted to recip-

rocate at an angle to the work acute in the direction of travel of said horizontally movable slide, a work engaging cutter on said inclined slide, an upright bracket secured to said inclined slide and projecting laterally thereof, a tracer mechanism mounted on said bracket with its longitudinal axis at right angles to the plane of said template and having a finger projecting longitudinally of said tracer mechanism engaging the profile of said template and responsive to lateral thrust relatively to said tracer mechanism in the plane of said profile and responsive to relief and impedance from said template, a hydraulic system including a cylinder and piston for reciprocating the inclined slide, said cylinder being secured to said inclined slide and said piston being joined to said inclined slide support, said system so connecting the tracer and the cylinder that actuation of the tracer finger by the template operates the cylinder to move the inclined slide to neutralize the actuation of said tracer finger, thus reproducing on the work the profile of said template, said finger being universally movable, said bracket being of hollow triangular shape with two of its spaced apexes secured to said inclined slide, and with said tracer secured adjacent the third apex thereof remote from said inclined slide.
